(57) **CLAIM**

I claim the ornamental design for a valved connector for medical lines, as shown and described.

DESCRIPTION

This application is also related to co-owned U.S. Design application Ser. No. 29/553,955, filed Feb. 2, 2016, entitled valved connector for medical lines.

FIG. 1 is a bottom perspective view of a valved connector for medical lines showing the new design;

FIG. 2 is a top perspective view thereof;

FIG. 3 is a bottom plan view thereof;

FIG. 4 is a top plan view thereof;

FIG. 5 is a front view thereof;

FIG. 6 is a left side view thereof;

FIG. 7 is a rear view thereof; and,

FIG. 8 is a right side view thereof.
